UNITED STATES PATENT OFFICE.

WILLIAM S. HUNKINS, OF HOLLYWOOD, CALIFORNIA.

TAB END.

Application filed December 28, 1926. Serial No. 157,474.

This invention relates to "tab ends", so called, for garments, and consists in a novel form of pin tube so constructed and combined with a piece of fabric as to form a 5 complete "tab end", the end of the tab carrying the metallic tube being so formed that no metal is exposed for contact with the body or clothing of the wearer. The main object of the invention is to provide an 10 proved construction which will admit of very rapid and economical production of finished tab ends.

In the drawings—

Fig. 1 is a view showing my improved 15 pin tube blank as associated with a strip of fabric preparatory to the final operation of forming the tab end;

Fig. 2 is a side view of the tab end in its finished form;

Fig. 3 is an end view of the tab end shown in Fig. 2;

Fig. 4 is a section on the line 4—4 of Fig. 3;

Fig. 5 is a plan view of the blank from 25 which the tab end bushing is made.

1 represents a plate of thin sheet metal of rectangular form. This plate is provided with slots 2—2 in the opposite edges thereof, and preferably about midway in the length 30 of said plate. 3 represents the main body of a piece of fabric which is to constitute the tab end. To assemble the plate 1 with the material 3, I place the plate 1 on the fabric and then tuck the edges 3^a—3^a into 35 the slots 2—2. The plate 1 may be folded as shown in Fig. 1, either before or after this tucking operation. I then roll the folded plate, shown in Fig. 1, into the tubular form shown in Figs. 1 to 4, which rolling 40 operation completes the process of assembling and produces the finished tab end in which the free ends of the fabric are brought together so that they may be conveniently applied to the garment to which the tab end 45 is to be attached. It will be noted that the metallic bushing is completely covered by the fabric so that it cannot contact with the

body or clothing of the wearer. It will also be noted that the bushing is of double thickness, which fact permits exceedingly thin 50 metal to be successfully used for bushing purposes.

I claim:

1. In a tab end, a sheet metal plate, the opposite edges of which are slotted, a strip 55 of fabric covering the back of said plate having its opposite edges folded into said slits and partly over the front surface of said plate at one side of said slits, said plate being folded upon itself to embrace between 60 the two layers thereof the aforesaid fabric folds, said plate and fabric being rolled into tubular form to produce a finished tab end with a fabric covered metallic bushing 65 in one end thereof.

2. In a tab end, a strip of fabric with its opposite side edges folded inwardly, a metallic plate folded to form a plate of double thickness with the folds of said fabric embraced between the two layers of said folded 70 plate, said plate and fabric being rolled into tubular form to produce a finished tab end with a fabric covered double thickness metallic bushing in one end thereof.

3. In a tab end, a sheet metal plate folded 75 intermediate its ends and slotted at opposite edges adjacent to said fold, a strip of fabric covering the back of said plate with its opposite edges folded into said slits and between 80 the two layers of said plate, said plate and fabric being rolled into tubular form to produce a finished tab end with a fabric covered metallic bushing in one end thereof.

4. In a tab end, a strip of fabric folded intermediate its length, a bushing seated in 85 the fold of said fabric strip, said bushing comprising a plate folded upon itself to form two thicknesses of metal rolled into tubular form with an open slit between the adjacent edges thereof, the said edges of the fabric 90 being tucked into the space between the two layers of metal and extending through the aforesaid slit.

WILLIAM S. HUNKINS.
